UNITED STATES PATENT OFFICE.

JOHN C. C. SCHEER, OF BEAVER FALLS, PENNSYLVANIA

SHOE-POLISHING MACHINE.

1,137,292.

Specification of Letters Patent. Patented Apr. 27, 1915.

Application filed May 25, 1914. Serial No. 840,803.

To all whom it may concern:

Be it known that I, JOHN C. C. SCHEER, a citizen of the United States of America, residing at Beaver Falls, in the county of Beaver and State of Pennsylvania, have invented certain new and useful Improvements in Shoe-Polishing Machines, of which the following is a specification, reference being had therein to the accompanying drawing.

This invention relates to shoe polishing machines, and has for its object to provide a machine of such class, in a manner as hereinafter set forth, with a polish applying mechanism capable when a shoe is drawn therethrough to apply polish to not only the heel portion of the upper, but to the instep and front portion, as well as to the sole and heel.

A further object of the invention is to provide a machine of such class, in a manner as hereinafter set forth, with a manually operable polishing mechanism for polishing the shoe after the latter has been submitted to the polish applying mechanism.

Further objects of the invention are to provide a manually operable shoe polishing machine which is comparatively simple in its construction and arrangement, strong, durable, efficient and convenient in its use, readily set up, and comparatively inexpensive.

With the foregoing and other objects in view, the invention consists of the novel construction, combination and arrangement of parts as hereinafter more specifically described and illustrated in the accompanying drawings, wherein is shown an embodiment of the invention, but it is to be understood that changes, variations and modifications can be resorted to which come within the scope of the claims hereunto appended.

In the drawings, wherein like reference characters denote corresponding parts throughout the several views: Figure 1 is a top plan view of a shoe polishing machine in accordance with this invention, Fig. 2 is a side elevation.

Referring to the drawings in detail, 1 denotes a supporting frame provided at its top with a longitudinally extending platform 2, which has its top face formed with a foot rest 3, and each of its side edges with longitudinally extending guide grooves 4.

The frame 1 intermediate its upper ends has formed integral therewith, a longitudinal cross bar 5, having a pair of bearings

6 and 7, the former being arranged in alignment with a bearing 8, and the latter in alignment with the bearing 9. The bearings 8 and 9 are formed in the bottom of the frame 1. Extending from the bearing 8, through the bearing 6 and the cross bar 5, is a stationary shaft 10, which projects above said bar 5, and has mounted thereon an oscillatory sleeve 11 provided with a crank arm 12. Mounted in the bearing 9 and extending through the bearing 7 and cross bar 5 is an oscillatory shaft 13, having fixed to its upper end a crank 14, which is connected to the crank 12 by a pitman 15. Fixed to the top of the sleeve 11, and oscillating therewith is a horizontally disposed flat plate 15^a, having each end thereof provided with an upwardly extending arm. The arms are indicated at 16 and 17, and the arm 17 is of greater height than the arm 16. The increased length of the arm 17 provides what may be termed a handle bar and which terminates in a handle or grip 18. The handle or grip 18 is disposed in a plane parallel to the plane of the plate 15^a. Hinged as at 19 to the arm 17 is an actuating member 20, and hinged as at 21 to the arm 16, is an actuating member 22. The plate 15^a, arms 16 and 17, members 20 and 22, sleeve 11, constitute the operating mechanism for the polishing mechanism.

The polishing mechanism includes a pair of oppositely disposed brushes 23, 24, which are segment-shaped in plan and are positioned over the foot rest 3. The body 24 of each of the brushes is hinged as at 25, to a carrier 26, which is fixed to the outer end of an actuating member and each of said actuating members, at its outer end is provided with a depending arm 27, having journaled thereon a guide roller 28, which travels in a groove 4. The lower end of each of the arms 27 is connected to the plate 15^a by an inclined coiled spring 29, and the function of said springs 29 is to assist in the reciprocation of the brushes against the shoe when the plate 15^a is oscillated. When polishing the shoe, the latter is placed upon the foot rest 3 between the brushes 23, 24, and the plate 15^a oscillated through the medium of the handle 18, such action causes the brushes to reciprocate against the shoe and polish the same. As the brushes are hinged, it is obvious that they are yieldable. The springs 29 further provide means for maintaining the brushes

in close contact with the shoe during the operation of polishing. After the polish has been applied to the shoe, the shoe is then acted on for the purpose of polishing it through the medium of the polishing mechanism.

What I claim is:—

1. A shoe polishing machine comprising a platform having each of its sides provided with a longitudinal groove and its upper face providing a foot rest, supporting means for said platform, an oscillating plate arranged below said platform and supported by said means, brush actuating members hinged to the ends of said plate, brushes hinged to the forward ends of said members, arms depending from said members, resilient connections between said arms and said plates, rollers carried by said arms and traveling in said grooves.

2. A shoe polishing machine comprising a platform having each of its sides provided with a longitudinal groove and its upper face providing a foot rest, supporting means for said platform, an oscillating plate arranged below said platform and supported by said means, brush actuating members hinged to the ends of said plate, brushes hinged to the forward ends of said members, arms depending from said members, resilient connections between said arms and said plates, rollers carried by said arms and traveling in said grooves, and a handle connected to said plate.

In testimony whereof I affix my signature in the presence of a witness.

JOHN C. C. SCHEER.

Witness:

MAX H. SROLOVITZ.
